UNITED STATES PATENT OFFICE

ROBERT BACK, OF CHICAGO, ILLINOIS, ASSIGNOR TO THE WAHL COMPANY, OF CHICAGO, ILLINOIS, A CORPORATION OF DELAWARE

DESIGN FOR A DESK PEN RECEPACLE

Application filed August 19, 1931. Serial No. 40,887. Term of patent 14 years.

To all whom it may concern:

Be it known that I, ROBERT BACK, a citizen of the United States, residing at Chicago, in the county of Cook and State of Illinois, have invented a new, original, and ornamental Design for a Desk Pen Receptacle, of which the following is a specification, reference being had to the accompanying drawing, forming part thereof.

The figure of the drawing is a side elevation of a desk pen receptacle showing my new design.

I claim:

The ornamental design for a desk pen receptacle substantially as shown.

ROBERT BACK.
